UNITED STATES PATENT OFFICE.

OTTO HEINS, OF NEW YORK, N. Y., ASSIGNOR TO BOSCH MAGNETO COMPANY, OF NEW YORK, N. Y., A CORPORATION OF NEW YORK.

MULTIPOLAR MAGNETO.

1,256,796.

Specification of Letters Patent. Patented Feb. 19, 1918.

Application filed December 24, 1915. Serial No. 68,506.

To all whom it may concern:

Be it known that I, OTTO HEINS, a subject of the Emperor of Germany, residing at and whose post-office address is 336 5 West 88th street, New York city, have invented certain new and useful Improvements in Multipolar Magneto; and I do hereby declare the following to be a full, clear, and exact description of the invention, 10 such as will enable others skilled in the art to which it appertains to make and use the same.

It was customary heretofore to use bipolar magneto for igniting the combustion mixtures in internal combustion engines and this arrangement was satisfactory for the usual four-cycle engines operating at ordinary speed, because the magneto and the gearing therefor operated well at crank 15 shaft speed for four cylinders and at one and one-half times crank shaft speed for six cylinders. However, for eight or twelve cylinder engines requiring a speed for a bipolar magneto of two or three times crank 20 shaft speed, and also for high speed engines of four or six cylinders operating at 2500 to 3500 R. P. M., the operation of the gearing is not entirely satisfactory and the magneto is more likely to miss on account of centrifugal force acting on the rotatable elements 25 of the mechanical interrupter.

The present invention is directed to a multipolar magneto, that is, one in which the armature and field have four or more poles each, and the object is to provide a magneto of small size capable of being attached to an engine for actuation thereby at comparatively low speed, the arrangement being such that any number of poles may 30 be provided without departing from the general design. Such a magneto may be driven directly by the crank shaft of the engine, thus eliminating magneto gearing, and distributing mechanism for distributing 35 the sparking voltages generated in the secondary winding may be carried by the rotatable member of the magneto and thereby eliminate the distributing gearing also.

My copending United States application 40 filed on even date herewith discloses a multipolar magneto having a field member composed of a continuous series of permanent magnets of U-form, whereas in the preferred construction in accordance with the invention forming the subject matter of this ap-

plication, the field member is composed of a plurality of bar magnets magnetically connected to pole pieces. Either the armature or the field may be rotated to generate periodically reversing voltage in the primary winding, and the mechanical interrupter is electrically connected to the winding to alter the circuit thereof at appropriate periods. Preferably, the armature poles are wound with secondary windings also, so 60 that high tension voltage suitable for producing sparks at spark gaps of jump-spark plugs may be generated directly in the magneto.

In the accompanying drawings illustrating the preferred construction in application to a six pole magneto for a twelve-cylinder four-cycle engine, wherein, as an example, the armature is rotatable and the distributor 70 brushes are carried thereby,

Figure 1 is a longitudinal section of the magneto on line 1—1 of Fig. 2;

Fig. 2 is a vertical section on line 2—2 of Fig. 1;

Fig. 3 represents a development in plan 30 of the field member;

Fig. 4 is an end elevation of the magneto with the cover of the mechanical interrupter removed; and

Fig. 5 is a wiring diagram.

The armature is fast on a rotatable shaft 1, and is made up of iron laminations bolted together and forming a central core 2 and six radially-disposed outwardly-projecting poles 3. A primary winding 4 and a secondary coil 5 are mounted on each pole.

The field member is stationary and is composed of six permanent magnets 6 of bar-form arranged in three circularly-extending series I, II, III magnetically insulated from 95 each other by being spaced apart. The magnets of each series are alternately-reversed so that adjacent ends of the magnets in the same series are of the same polarity, 7 representing the poles of one sense, 100 say north, and 7' representing the poles of the opposite sense. (See Fig. 3). The pole pieces 8 and 8', of soft iron, magnetically connect the adjacent ends 7 and 7', respectively, of the magnets, and form a continuous 105 series of six equally spaced poles of alternating polarity throughout and co-operative with the armature poles 3. The pole pieces extend across the three series of magnets, I, II, III, and each pole piece is fastened to 110

the adjacent ends of the magnets of but one series, the rear faces of each pole piece being recessed opposite the magnets of the other series so as to be magnetically insulated 5 therefrom.

In order that the permanent magnets 10 may be stronger than they would otherwise be, their ends are attached to those pole pieces which are separated by two other pole pieces, so that the magnets are long in comparison with their cross section; and in order to reduce the tendency of the magnetic flux 15 to pass around the field member without entering the armature, the adjacent ends of the magnets are separated and the rear faces 20 of the pole pieces 8 and 8' are recessed between the ends. In this way, a multipolar permanent magnet field of much magnetic strength is obtained in a small space, while the leakage and divergence of the flux from the armature is reduced.

The side plates 9 of non-magnetic material, such as aluminum, abut the side faces 25 of the outer series I and III of the magnets and are clamped thereto by cross bolts 10 which pass between the pole pieces. Each of the pole pieces is fastened by the screws 11 to the proper magnets at the ends thereof, so that when the nuts on the ends of the 30 cross bolts are screwed home, the entire field member is held rigidly in position relatively to the shaft 1, as a result of the fact that the side plates are rigid with the shaft bearings 12. The magneto is provided with a 35 base or stand 13 depending from the side plates, and a strap 14 of non-magnetic material encircles the magnets. The magneto shown in the drawing is about seven inches in diameter.

40 The mechanical interrupter for periodically interrupting the circuit of the primary winding 4 comprises the grounded interrupter element 15 and the insulated element 15', mounted for rotation with the armature, 45 and the six equally-spaced interrupter cams 16 carried by a normally stationary cam ring 17 provided in the well known way with means (not shown) for adjusting at will its circumferential position to advance 50 or retard the period of ignition. The six primary coils 4 are connected in series, one terminal being connected to the interrupter element 15' and the other terminal being grounded. A coil condenser 18 is mounted 55 fast on the shaft 1, and is connected between the insulated interrupter element and the ground.

The six secondary coils 5 are connected 60 in series and the two insulated terminals are connected respectively to the two spring-pressed distributor brushes 19 and 19', which are carried by the armature for rotation therewith. There is a series of spark plug 65 distributing contacts 20 and 20' at each end of the armature coöperative with the indi-

vidual brushes 19 and 19'. These contacts are embedded in plates 21 of insulating material fixed in position to the side plates 9, each contact being connected to an individual binding post 22.

70

The magneto shown is intended to be driven directly by the crank shaft of a twelve-cylinder four-cycle engine, and the twelve binding posts 22 electrically connected to the insulated electrodes of spark plugs 75 in the individual cylinders, as shown in Fig. 5. As in ordinary bipolar magnetos for ignition systems, an ignition voltage is generated substantially in the period in which the armature poles bridge the spaces 80 between adjacent field poles, the circuit of the primary winding being opened by the mechanical interrupter at the moment of ignition as a result of engagement between the deflecting interrupter lever 15 and a cam 85 16. In each rotation of the magneto herein shown, this occurs six times, and accordingly six ignition voltages are generated in the secondary winding. During each period of ignition, the distributing brushes 19 and 19' engage two spark-plug distributing contacts 20 and 20', and the sparks occur simultaneously at the two spark plugs connected in series with the secondary winding at that time, the arrangement being such that the 95 piston of one of the cylinders in which a spark occurs is in the explosion stroke, while the piston of the other cylinder is in its exhaust stroke.

It will be apparent from the foregoing, 100 that a magneto of the same general design may be provided with 4, 8, 12 or other suitable number of poles, and, if desired, the magneto may be driven by the engine through speed change gearing, the number 105 of poles being properly selected to furnish ignition voltages at appropriate periods. It will also be apparent that, if desired, the type of magneto herein disclosed may be associated with distributing mechanism of 110 the ordinary kind driven from the magneto through two to one speed reducing gearing for four-cycle engines.

What I claim is:

1. In a multipolar magneto for electric 115 ignition systems, an armature having a generating winding, a mechanical interrupter electrically connected to the generating winding, and a field member composed of a series of pole pieces coöperating with the 120 armature and a plurality of series of alternately-reversed bar magnets of arcuate form magnetically connected to the pole pieces, the magnets of one series overlapping the magnets of another series; substantially as 125 and for the purpose described.

2. In a multipolar magneto for electric 130 ignition systems, an armature having a generating winding, a mechanical interrupter electrically connected to the generating

winding, and a field member composed of a series of pole pieces coöperating with the armature and a plurality of series of alternately-reversed bar magnets of arcuate form 5 magnetically connected to the pole pieces, each magnet being connected to pole pieces separated from each other in the series by at least one other pole piece; substantially as and for the purpose described.

10 3. In a multipolar magneto for electric ignition systems, an armature having a generating winding, a mechanical interrupter electrically connected to the generating winding, and a field member composed of a series of pole pieces coöperating with the armature and a plurality of series of alternately-reversed bar magnets of arcuate form magnetically connected to the pole pieces, the magnets of one series being magnetically 15 insulated from the magnets of another series and overlapping them; substantially as and for the purpose described.

4. In a multipolar magneto for electric ignition systems, an armature having a generating winding, a mechanical interrupter electrically connected to the generating winding, and a field member composed of six pole pieces of alternating polarity coöperating with the armature, and three series of magnets of arcuate form wherein 20 each series is composed of two alternately-reversed magnets magnetically connected to opposite pole pieces and magnetically insulated from the remaining pole pieces.

35 5. In a multipolar magneto for electric ignition systems, an armature, and a field member composed of a continuous series of pole pieces coöperating with the armature and a plurality of magnetically-insulated 40 series of bar magnets, the magnets of each series being alternately-reversed and overlapping the magnets of a different series, and the magnets of the different series being magnetically connected to different pole pieces in such manner as to give them alternating polarity throughout.

6. In a multipolar magneto for electric ignition systems, an armature having radially-disposed poles, and a ring field member composed of a continuous series of pole pieces coöperative with the armature poles and a plurality of magnetically-insulated 50 series of circularly-extending bar magnets, the magnets of each series being alternately-reversed and overlapping those of another series, and the magnets of the different series being magnetically connected to different pole pieces in such manner as to give them alternating polarity throughout.

60 7. In a multipolar magneto for electric ignition systems, an armature, and a field member therefor having a plurality of series of circularly-extending bar-magnets and a continuous series of pole pieces coöperating with the armature, the magnets of

each series being alternately-reversed, and the ends of each bar magnet being magnetically connected to those pole pieces which are separated from each other by other pole pieces for the purpose described.

70 8. In a multipolar magneto for electric ignition systems, an armature member having projecting poles wound with primary and secondary windings, a mechanical interrupter electrically connected to the primary 75 winding, and a field member having a plurality of magnetically insulated series of alternately-reversed magnets of arcuate form, and a continuous series of pole pieces each magnetically connecting the magnets of selected series so as to alternate in polarity throughout the series.

9. In a multipolar magneto for electric ignition systems, an armature member having projecting poles wound with primary 80 and secondary windings, a mechanical interrupter electrically connected to the primary winding and a field member having a plurality of magnetically insulated series of alternately-reversed magnets of arcuate 85 form wherein the magnets of one series overlap the magnets of another series, and a continuous series of pole pieces magnetically connected to the magnets so as to alternate in polarity throughout the series.

95 10. In a multipolar magneto for electric ignition systems, an armature, and a field member therefor having a plurality of series of alternately-reversed magnets of arcuate form and a series of pole pieces extending across the magnets and magnetically connecting certain of the magnets so as to alternate in polarity throughout the series, the magnets of each series being arranged end to end and the rear faces of the 100 pole pieces being recessed between the adjacent ends of the magnets to which they are connected.

11. In a multipolar magneto for electric ignition systems, an armature, and a field 110 member therefor having a plurality of series of alternately-reversed magnets of arcuate form and a series of pole pieces extending across the magnets in coöperation with the armature, each of said pole pieces magnetically connecting the adjacent ends of certain magnets and being magnetically insulated from the other magnets 115 as to alternate in polarity throughout the series.

12. In a multipolar magneto for electric 120 ignition systems, an armature, and a field member therefor having a plurality of series of alternately-reversed magnets of arcuate form and pole pieces extending across the magnets in coöperation with the armature 125 and magnetically connecting adjacent ends of certain magnets, each of said pole pieces being recessed between the adjacent ends of those magnets to which it is magnetically connected and also being recessed opposite 130

the other magnets so as to be insulated therefrom.

13. In a multipolar magneto for electric ignition systems, an armature, and a field member therefor having three series of alternately-reversed magnets of arcuate form wherein the magnets of each series overlap the magnets of the other two series, and six pole pieces extending across the magnets in

coöperation with the armature, each of said 10 pole pieces magnetically connecting the adjacent ends of the magnets of one series and being recessed between those ends and also being recessed opposite the magnets of the remaining series so as to be magnetically insulated therefrom. 15

In testimony whereof I affix my signature.
OTTO HEINS.
